TRENCHING DEVICE

Charles M. Knowles, St. Petersburg, Fla.

Application August 1, 1955, Serial No. 525,532

4 Claims. (Cl. 37—99)

This invention relates to a ditcher or trenching device, and more specifically, the invention pertains to trenching or excavating apparatus.

One of the primary objects of this invention is to provide a machine for the excavation of a trench of predetermined width and depth.

Another object of this invention is to provide ditching apparatus for the excavation of a trench of predetermined width and depth to receive cement for the footings of buildings.

A further object of this invention is to provide a trenching device of the type referred to above with power driving means including means for raising the trenching device into its inoperative position and for lowering it into its operable position.

A still further object of this invention is to provide a trenching device with means for dispatching the excavated earth to a side of the trench.

This invention also contemplates the provision of a trenching device with means for squaring or cleaning out intersecting corners of a trench.

It is a still further object of this invention to provide a ditching or trenching device of the type referred to above which may be easily installed upon conventional tractors or other similar vehicles, the device being economical to manufacture, non-complex in construction and assembly, and durable in use.

Other and further objects of this invention will become more evident from a consideration of the following specification when read in conjunction with the annexed drawings, in which:

Figure 1 is a side elevational view of a trenching device constructed in accordance with this invention.

Figure 2 is a top plan view of the trenching device shown in Figure 1.

Figure 3 is a cross-sectional view taken on the vertical plane of line 3—3 of Figure 1, looking in the direction of the arrows.

Figure 4 is an enlarged fragmentary detail perspective view illustrating certain assembly details of this invention.

Figure 5 is a diagrammatic illustration showing the manner by which the intersecting corners of a trench are cleared and squared.

Figure 6 is an enlarged perspective view of the impeller removed from its support.

Referring now more specifically to the drawings, reference numeral 10 designates, in general, a ditching or trenching device constructed in accordance with the teachings of the instant invention.

The trenching device 10 is seen to comprise a substantially U-shaped frame 12 formed of suitable material and having a T-shaped transverse cross-sectional configuration including the continuous web 14 and crosshead 16 therefor. As is seen in the drawings, the frame 12 includes a pair of spaced substantially rectangular arms 18, 20 having one of their respective adjacent ends connected to a bight member 22. The outer ends of the

2

arms 18, 20 are bent laterally away from each other to form the flanges 24, 26, respectively.

The flanges 24, 26 are bent again, forwardly, to form end extensions 28, 30, and the latter are centrally apertured at 32, 34, respectively, to receive the pivot pins 36, 38 for pivotal connection with the ends of a pair of levers 40, 42 connected with and forming part of the conventional hydraulic lift of a tractor or other similar vehicle.

Accidental or inadvertent displacement of the pivot pins 36, 38 is prevented by the diametrically extending cotter pins 44, 46. The bight 22 is cut away intermediate its ends to serve a function to be described below, and the web portion 14A thereof is provided with a substantially rectangular, laterally extending plate 48.

A pair of spaced, parallel and substantially rectangular side plates 50, 52 have their respective lower ends fixedly secured, as by welding, to the marginal edge portions at the opposite ends of the plate 48 and extend across and are secured to the adjacent portions of the web 14A. A substantially rectangular front plate 54 is disposed between the confronting ends of the bight 22 and is welded thereto as well as to the adjacent side of the web 14A.

A pair of spaced, parallel and elongated hollow tubular pipes 56, 58 have one of their respective ends welded to the upper ends of the plates 50, 52, respectively, and to the adjacent portions of the front plate 54. A top plate 59 is welded or otherwise secured to the upper side of the pipes 56, 58 and to the adjacent portions of the front plate 54.

The pipes 56, 58 project rearwardly and are fixedly secured to a horizontally elongated substantially U-shaped channel member 60 forming one element of a rear frame 62. A pair of spaced parallel flat plates 64, and 66 and a second pair of spaced parallel flat plates 68, 70, extend between and are fixedly secured to the opposite ends of the channel members 60 and 72. Each pair of plates 64—66 and 68—70 is provided with aligned apertures 74, 76 and 78, 80 to serve a function to be described, and each pair of plates 64—66 and 68—70 is adapted to receive therebetween vertical standards 82, 84 respectively. The standards 82 and 84 are provided with a plurality of vertically spaced transversely extending openings 86 which are adapted for selective alignment with the apertures 74, 76 and 78, 80 respectively to receive therethrough the pins 88, 90 which are held against accidental or inadvertent axial displacement by the cotter pins 92, 94.

The trenching tool or implement 96 comprises a plowshare 98 having a V-shaped recess 99 formed in the leading end thereof, an integrally formed arcuate heel 100, a pair of vertically extending moldboards 102, 104; and a second, reversely extending, plowshare 106 having an arcuate heel 108, and the upper end thereof pivotally mounted at 105 to the standards 82, 84. The sides of the heel 100 are rigidly secured between the moldboards 102, 104 and the unit 96 is pivotally connected on the lower ends of the standards 82, 84 by bolts 110 locked by nuts 112.

Each of the moldboards 102, 104 is provided with an arcuate slot 114 which registers with an opening (not shown) formed in the standards 82, 84 which receive therethrough bolts 116 that are locked by nuts 118. The slot 114 affords means whereby the pitch of the plowshares 98 and 106 may be adjusted, and the pivotal mounting 105 of the plowshare 106 makes it possible to swing it upwardly when not in use. Conventional means, not shown, hold the plowshare 106 in its elevated position, whereby the front plowshare 98 may enter the ground at a steep angle.

An angle iron 120 has one of its sides 122 rigidly

secured to the underside of the plate 48, while the other side 124 depends therefrom. The angle iron 120 is provided with a reinforcing web 126 which is disposed intermediate a pair of openings (not shown), the openings receiving therethrough a pair of bolts 128 which extend through vertically elongated slots 130 formed in the stem 132 of an inverted substantially T-shaped angle iron 134. The angle iron 134 is also provided with a reinforcing web 136 and is locked in adjusted position by the nuts 138.

The crosshead 140 of the angle iron 134 is substantially rectangular in configuration and has welded to the underside thereof an elongated substantially hollow cylindrical bearing housing 142. A bearing sleeve 144 is disposed within the housing 142 and journals an intermediate portion of an impeller shaft 146 therein.

An impeller 150 having three sets of blades 150A, 150B, and 150C integrally formed with a hub 154 is fixedly secured to the rear end of the shaft 146. The sets of blades are staggered with respect to each other and the three blades 150A comprise sod cutters which are followed by the three wide earth broadcasting impellers 150B and the three follower blades 150C.

The front or forward end of the shaft 146 has fixedly secured thereto the female element 158 of a universal joint 160. The male unit 162 of the joint 160 is fixedly secured to one end of a power take off drive shaft 164 of a conventional tractor (not shown), or other similar vehicle.

A pair of bars 166, 168 are fixedly secured to the opposite sides, respectively, of the top plate 59 in spaced substantially parallel relation. The bars 166, 168 have their respective forward ends converging inwardly and upwardly at 166A, 168A and terminate in spaced substantially parallel and proximate relation at 166B, 168B. The elements 166, 166A, 166B and 168, 168A and 168B comprise a yoke 170 which is pivotally mounted on a pivot pin 171 that extends diametrically through the spherical boss 172 carried on the outer end of a conventional hydraulic lift rocker arm 174 of a tractor. The bars 166, 168 also have rearwardly extending portions 166C, 168C which are welded to the upper sides of the pipes 56, 58 and to the U-shaped channel member 60. The side plates 50, 52 have integrally formed rearwardly extending braces 51, 53 which are welded to the underside of the pipes 56, 58 and their ends rigidly connected to the U-shaped channel member 60.

A pair of bracket arms 176, 178 are secured to the outer ends of the arms 18 and 20, respectively, by means of the bolts 180, 182, and depend therefrom. Each of the bracket arms 176, 178 are provided with cutting discs 184, 186, respectively, which are mounted on the lower ends thereof on axles 188.

In operation, the pitch of the plowshare 98 is adjusted to the desired angle and the vertical standards 82, 84 are secured in their selective adjusted position to control the depth of the trench 190. The trenching tool 96 is now lowered by the hydraulic lift which forces the cutting discs 184, 186 into the ground. The tractor is then placed into movement and the plowshare 98 is drawn into the ground along the inclined grade 192. When the desired depth is reached, the control valve for the hydraulic lift is actuated to maintain the plowshare 98 in fixed position.

The moldboards 102, 104 mold the size of the trench which has been previously cut by the cutting discs 184, 186, and the earth moving upwardly along the arcuate heel 100 is distributed on one side of the trench 190 by the impeller 150.

Should the depth of the trench be of considerable degree, the pins 88 and 90 are withdrawn to lower the plowshare when the hubs of the discs 184, 186 contact the ground or when the lowermost position of the hydraulic system has been reached.

In order to square and clean out intersecting corners

of the trench 190, the plowshare 106 is lowered to its full line position and the tractor is reversed causing the plowshare 106 to engage the earth until the end or the corner of the trench is reached as is illustrated in dotted lines in Figure 5 of the drawings. At that time the hydraulic lift is operated raising the levers 40 and 42 and the arm 174 moving the yoke 170 upwardly to effect pivotal and upward movement of the plowshare 106 about the pivot pins 36, 38.

Having described and illustrated one embodiment of this invention in detail, it will be understood that the same is offered merely by way of example, and that this invention is to be limited only by the scope of the appended claims.

What is claimed is:

1. In combination with a tractor having a power take off shaft and a hydraulic lift mechanism, a trenching device, said trenching device comprising a front and rear frame, means rigidly connecting said frames together, a pair of cutting ground engaging discs, means mounting said cutting discs for rotation on said front frame, means connecting a plow on said rear frame in depending relationship relative thereto, an impeller mounted on said front frame above said plow for distributing the earth from said plow, means connecting said impeller for rotation with said power take off shaft, and means pivotally connecting said front frame with said hydraulic lift mechanism.

2. A trenching device comprising a substantially U-shaped front frame including a pair of spaced arm members having a pair of their respective adjacent ends connected with a bight member, a bracket arm fixedly secured to each of said arms of said frame and depending therefrom, a ground engaging disc rotatably mounted on each of said depending bracket arms, an impeller mounted for rotation on said front frame, a rear frame, means rigidly securing said front frame to said rear frame, a vertical standard for each side of said rear frame, a plow mounted on the lower ends of said vertical standards, means disposed adjacent the upper ends of said standards for selectively vertically adjusting the plow relative to said rear frame, said plow being disposed below said impeller, said impeller distributing the earth from said plow, and a yoke having one of its ends fixedly secured to said front frame, the other end of said yoke extending upwardly and forwardly therefrom.

3. A trenching device comprising a substantially U-shaped front frame including a pair of spaced substantially parallel arms, said arms having one of their respective adjacent ends connected with a bight member, a plate fixedly secured to said bight member and projecting vertically therefrom, a pair of spaced substantially parallel pipes having one of their respective adjacent ends fixedly connected to said plate, said pipes projecting rearwardly from said plate, a rear frame, means fixedly securing said rear frame to said other ends of said pipes, a pair of vertically extending standards mounted in and depending from said rear frame in laterally spaced relation, a plow fixedly secured to the lower ends of said vertical standards, means at the upper ends of said standards for securing said plow in vertically adjusted position relative to said rear frame, an impeller mounted for rotation on said front frame for distributing the earth from said plow, a bracket arm adjustably mounted on each of said arms of said U-shaped frame, respectively, said bracket arms depending from said arms of said frame and having rotatably mounted on the lower ends thereof a pair of ground engaging discs, and a yoke fixedly secured to said plate, said yoke projecting upwardly and forwardly of said plate.

4. A trenching device comprising a substantially U-shaped frame including a pair of spaced substantially parallel arms having one of their respective adjacent ends connected by a bight member, said bight member having a rearwardly projecting substantially rectangular plate integrally formed therewith, a vertically extending plate

disposed at each side of said last named plate, a front plate fixedly secured to said bight member and to said pair of plates, a pipe fixedly secured to the upper ends of each of said vertically extending plates and to said front plate, a top plate fixedly secured to the upper side of said pair of pipes and to said front plate, said pipes having their respective other ends fixedly secured to a substantially U-shaped channel member, a pair of flat plates for each end of said channel member, said flat plates having one of their respective ends fixedly secured to said channel member and the other ends thereof projecting away therefrom, said other ends of said flat plates being fixedly secured to the opposite ends of a second U-shaped channel member, a vertical standard slidably disposed between each of said pairs of flat plates, means for supporting said standards in adjusted vertical position, a plow mounted on said vertical standards adjacent the lower ends thereof and on one side thereof, a second plow mounted on said standards adjacent the lower ends thereof on the opposite side thereof, said second plow facing in a direction re-

verse to the direction said first plow faces, a moldboard for each side of said plows, means mounting one of said plows and said moldboards for pivotal adjustment on said standards, an impeller mounted for rotation on said bight member for distributing the earth from said plow, a bracket arm depending from each of said arms of said U-shaped frame, a ground engaging disc mounted for rotation on the lower end of each of said bracket arms, and a yoke having one of its ends fixedly secured to said top plate and projecting upwardly and forwardly thereof.
